LIQUID APPLICATOR

Henry J. Brownstein, Chicago, Ill.

Application September 14, 1939, Serial No. 294,824

3 Claims. (Cl. 91—39)

The object of this invention is to provide an improved liquid applicator which may be used to advantage in applying liquid wax and other materials to floors and other surfaces.

The improved applicator is so constructed as to distribute the liquid uniformly with full and accurate control at all times over the rate of distribution. It is inexpensive to manufacture, light in weight, durable, easy to manipulate, will hold a large quantity of the liquid, will not leak, and can be taken apart readily for cleaning and replacement of the bottom pad.

While the foregoing statements are indicative in a general way of the nature of the invention, other more specific objects and advantages will be apparent to those skilled in the art upon a full understanding of the construction of the improved applicator.

A preferred embodiment of the invention is presented herein for the purpose of exemplification, but it will of course be appreciated that the invention is susceptible of being incorporated in other structurally modified forms coming equally within the scope of the appended claims.

In the accompanying drawings:

Fig. 1 is a perspective view of a liquid applicator constructed in accordance with the invention;

Fig. 2 is a vertical transverse section through the applicator shown in Fig. 1, taken on the line 2—2 of Fig. 1;

Fig. 3 is a vertical longitudinal section through the applicator taken on the line 3—3 of Fig. 2;

Fig. 4 is a horizontal section, taken on the line 4—4 of Fig. 2;

Fig. 5 is a bottom plan view of the applicator, with a portion of the bottom pad broken away to show the bottom plate.

Fig. 6 is a fragmentary bottom plan view of the control valve; and

Fig. 7 is a vertical transverse section through the lower portion of the casing and the bottom plate, taken on the line 7—7 of Fig. 3.

The device shown in the drawings includes a casing 10, a manipulating handle 11, a bottom plate 12 and a bottom pad 13. The casing 10, which is preferably made of aluminum to reduce its weight, contains a tank 14. The bottom 15 of this tank is spaced somewhat above the lower edge 16 of the casing, and the casing below the bottom 15 of the tank is characterized by a downwardly extending flange 17 of elongated rectangular form. The handle 11 is pivotally attached by bolts 18 to ears 19 on the lower portion of the back of the casing and is movable from the inclined operating position shown in Fig. 1

to the upright out-of-use position shown in Fig. 2. The handle 11 is releasably held in the position shown in Fig. 3 by means of a locking rod 20 which is carried by the lower portion of the handle and is projectable into the uppermost one 5 of two or more notches 21 on one of the ears 19 when the handle is in its straight up position. The locking rod 20 is held against inadvertent movement in any position in which placed by a small spring-pressed ball 22 which is mounted in 10 the handle adjacent the rod and bears frictionally against one side of the latter.

The tank 14 is filled from the top through an aperture 23, which aperture is normally closed by a readily removable cap 24. The cap 24 15 tightly seals the aperture 23, and is preferably unvented so as to permit the applicator to be inverted without any leakage occurring, the nature of the hereinafter described valve serving to admit sufficient air to the tank to assure a free flow 20 therefrom. The edge of the casing just above the aperture 23 is preferably formed into a cone 25 which facilitates filling of the tank 14 with the wax or other liquid without any spilling.

The bottom 15 of the tank 14 is provided at 25 approximately its center with an opening which overlies a valve seat 26 provided in a plate 27 secured to the underside of the bottom. This seat 26 cooperates with a vertically movable valve 28 which is carried by the plate 27. When the 30 head of the valve 28 is in its lowermost position, in engagement with the seat 26, the liquid in the tank 14 is prevented from flowing downwardly out of the same. When the valve 28 is raised, the liquid is permitted to flow downwardly 35 through the seat 26, the rate of flow depending on the extent to which the valve is raised. The valve 28 has a downwardly projecting stem 29 which extends through a relatively large aperture 30 in an arm 31 secured to a rock shaft 32. The 40 rock shaft 32 is journaled in ears 33 formed on the plate 27 and is provided at one end with a downwardly extending arm 34 to which a tensioned coil spring 35 is attached.

Cotter pins 36 extend through the stem 29 of 45 the valve, just above and below the arm 31, for transmitting movement of the arm 31 to the stem 29. The spring 35 acts through the arm 34, shaft 32 and arm 31 to hold the valve 28 yieldingly against the seat 26. When it is desired to release 50 some of the wax or other liquid the valve 28 is lifted from the seat 26 by a flexible wire 37 which is connected to the arm 34 and extends through a flexible guide conduit 38 from the casing up into the handle 11. At the upper end of the handle the 55

wire 37 is connected with a trigger-like finger piece 39 which when pulled will move the wire 37 and open the valve 28 against the resistance of the spring 35. The offset of the pivot 18 for the handle with respect to the point 40 at which the conduit 38 enters the casing is such as to force a certain amount of slack in the wire 37 when the handle 11 is moved into its straight up out-of-use position, and this slack is sufficient to prevent the valve 28 from being operated by the finger piece 39 when the handle is in that position, thereby eliminating the possibility of any inadvertent opening of the valve when the applicator is not actually in use.

15 The plate 12 is of the same rectangular shape as the flange 17 which extends about the lower portion of the casing, and underlies the edge 16 of the flange 17, closing the otherwise open bottom of the casing between the elevated bottom 20 15 of the tank 14 and the lower edge 16 of the flange. This bottom plate, like the casing 10, is preferably made of aluminum and is characterized by an upwardly opening trough 41 which extends substantially from one end of the plate to 25 the other. This trough is centered beneath the valve 28 and slopes downwardly from its center toward each of its ends, which ends 42 and 43 are closed. The trough 41 is provided at regular intervals in its bottom with small ports 44. The 30 bottom plate 12 is provided, directly beneath the ported bottom of the trough 41, with a downwardly opening channel 45 into which the wax or other liquid is metered, and is provided, at opposite sides of the trough adjacent the longer 35 35 side flanges 17, with upwardly and outwardly inclined flanges 46 for centering the bottom plate within the open bottom of the casing.

The bottom pad 13 is a rectangular piece of material, preferably lamb's wool. This pad is positioned against the under surface of the bottom plate 12 and is characterized by extensions 47 along its longer sides which are folded back about the longer sides of the bottom plate and tucked beneath the centering flanges 46. The pad 13 is held in this position by being clamped between the upper edges of the plate 12 and the lower edge 16 of the casing at the bottom of the flange 17. The plate 12 is removably held in this clamped position by the engagement of a lug

48 on one end of the plate with an underlying lug 49 on the corresponding end of the casing. The other end of the plate is held by a pin 50 in the casing which extends into an aperture 51 in the plate. The bottom pad 13 is provided at intervals longitudinally of the center of the same with apertures 52. These apertures are located directly below the distributing channel 45 in the bottom plate, preferably in vertical register with the ports 44 in the bottom of the trough 41. 10

I claim:

1. A liquid applicator of the type described, comprising a casing having a tank in the upper portion thereof and a downwardly opening recess beneath the tank, a valve in the bottom of the tank, a readily removable bottom plate beneath the lower edge of the casing over the recess, an apertured trough on the bottom plate within the recess below the valve, and a pad beneath the bottom plate provided with reversely bent opposite edge portions which are releasably clamped between the lower edge of the casing and the bottom plate. 15

2. A liquid applicator of the type described, comprising a casing having a tank in the upper portion thereof and a downwardly opening recess beneath the tank, a valve in the bottom of the tank, a bottom plate beneath the lower edge of the casing over the recess, an apertured trough on the bottom plate within the recess below the valve, and a pad beneath the bottom plate, said trough being inclined downwardly from its center toward its ends, said bottom plate being provided beneath the trough with a downwardly opening distributing channel, and said pad extending across said channel. 20

3. A liquid applicator of the type described, comprising a casing having a tank therein, an apertured bottom plate beneath the tank, a pad beneath the bottom plate, a valve in the bottom 40 of the tank above the apertured bottom plate, a manipulating handle movable from an upright out-of-service position to an inclined operating position, a finger piece on the handle connected with the valve for opening the latter, and means 45 for preventing opening of the valve by the finger piece when the handle is in its upright position.

HENRY J. BROWNSTEIN.
